PLATEN ROLLER SUPPORT

Merle F. Myers, Detroit, Mich.

Application October 25, 1949, Serial No. 123,430

8 Claims. (Cl. 51—135)

1

This invention relates to devices for supporting and guiding work relative to an abrasive belt on a grinding machine or the like and particularly to an attachment for such machines for stabilizing the belt and the work as the grinding operation proceeds. This application forms a continuation-in-part of a co-pending application for U. S. patent, Serial No. 109,201, filed August 8, 1949, now abandoned, and entitled "Platen Roller Support."

An important object of the invention is to provide a device for use with conventional grinding machines employing an endless belt as a polishing or grinding element which serves in a novel manner to guidingly support the work in its movement relative to the belt and which is designed in a novel manner for backing up and stabilizing the belt during the interval of time in which the work is in contact therewith. Another important object of the invention is to provide an improved attachment for a grinding machine and the like which may be readily attached to such machines and function to support work as the edges thereof are ground or beveled to a desired amount. A further important object of the invention is to provide an attachment of this character which is composed of few parts designed for inexpensive manufacture and which is durable and functions expeditiously for the purposes intended.

In carrying out the objects of the invention the device is preferably in the form of a removable attachment adapted to be conveniently secured to a fixed member of a grinding machine having an endless vertically traveling belt and to be supported thereby with one part disposed in juxtaposition to the rear face of the belt and another part disposed across the front face of the belt to receive and support the work thereon. The part of the device which is disposed adjacent to the rear face of the belt is composed of two members spaced longitudinally apart with respect to the belt and arranged so that two spaced areas of the belt are engageable therewith during the grinding operation. The forward part of the device extends across the front face of the belt on a level between the belt engaging members on the rear side thereof and is provided in a novel manner with one or more freely movable elements which support the work and guide the work for movement transversely to the direction of movement of the belt. Such last means preferably comprises a plurality of rollers arranged in a row and independently rotatable about parallel axes extending perpendicular to the plane of the belt. The rollers function to support the work, such as a sheet of glass, and permit the work to be moved to and

2

from across the face of the belt while it is pressed into engagement therewith. A novel feature of the invention is the provision of a demountable connection for conveniently detaching the roller supporting part of the device from the balance of the device in order that the front face of the belt may be clear of any obstruction when so desired.

Various other objects, advantages and meritorious features of the invention will become more fully apparent from the following specification, appended claims and accompanying drawings, wherein:

Fig. 1 is a top plan view of one embodiment of the invention and showing the same secured to a fixed member of a grinding machine frame.

Fig. 2 is a front elevation of the device of Fig. 1.

Fig. 3 is a side elevation of the device, showing the belt and alternative positions of work in dotted outlines.

Fig. 4 is a fragmentary side elevation of a part of the device illustrating particularly the manner by which the rear supporting arm is connected to the rest of the attachment.

Fig. 5 is a front elevation of a modification of the invention.

Fig. 6 is a top plan view of the attachment of Fig. 5 showing the same secured to a tubular member of a grinding machine frame.

Fig. 7 is a side elevation of the attachment of Figs. 5 and 6 showing the grinding belt in dotted outline.

Fig. 8 is a fragmentary front elevation showing a modification of the work supporting elements; and,

Fig. 9 is a vertical sectional view taken along line 9—9 of Fig. 8.

Referring to the drawings wherein like numerals designate similar parts throughout various views, a fixed part of a grinding machine frame, such as a tubular member, is indicated at 10. Slidably supported on the tubular member 10 is a sleeve or collar 12 which is provided with a set screw 14 for adjustably positioning the collar on the member 10. A U-shaped member having legs 16—16 and a connecting web portion 18 is secured to the collar 12 as by welding 20. Preferably, however, the middle portion of the web 18 is secured by welding to the outside of the collar 12 so that the plane of the web 18 extends parallel to the axis of the collar as shown in Fig. 3. Secured to the outer extremity of each leg 16, as by welding 22, is a belt engaging member or shoe plate 24 to the outer surface of which is secured a suitable lining 26. The linings 26 may be secured to the shoe plates by copper rivets

28 in the manner indicated in Fig. 3. The upper and lower marginal edges of the shoe plates 24 and linings 26 are bent rearwardly as at 30 for the purpose to be later set forth.

A supporting member or bracket 32 is secured to the web portion 18 by a suitable fastening element such as the bolt 34. Preferably the bracket 32 is connected to the web portion 18 below its point of connection to the collar 12 as shown in Fig. 3. An arm 36 is removably connected to the supporting bracket 32 in the manner hereinafter described. The arm 36 as shown in Fig. 1 is bent at right angles intermediate its ends so as to project a part thereof parallel to the plane of the two shoe plates 24-24 but in forwardly offset relation thereto. The arm 36 is provided with a plurality of laterally extending pins 38 which are disposed in a horizontal row and in spaced parallel relationship. Each pin carries a correspondingly shaped roller 40 which is preferably formed of deformable material such as rubber and which is removably retained on the pin by a washer 42 and a cotter pin 44. The rollers 40 are of the same size and in assembled position they extend in a horizontal row. The arm 36 is provided with an upwardly opening notch 46 for a purpose to be set forth hereinafter.

The roller supporting arm 36 is detachably mounted on the bracket 32 and for this purpose, as shown in Figs. 3 and 4 the arm is provided with slots 48 and 50 which are preferably mutually perpendicular and adjacent to the edges of the arm 36. The supporting bracket 32 is provided with projecting headed elements 52 and 54 which are slidably received in the slots 48 and 50 respectively. The arm 36 is cut away as at 56 adjacent to the slot 48 to permit the arm to be readily moved from the position shown in Fig. 4 to the position shown in Fig. 3 with the headed portions of the elements extending through the slots and engaging the side of the arm 36. This mode of adjustment enables the arm 36 to be quickly removed and installed and at the same time provides a rigid support therefor.

In mounted relationship to the grinding belt, such as indicated in dotted outline at 58, it will be seen that the linings 26 on the shoe plates 24 are disposed opposite to the rear face of the belt while the rollers 40 are disposed in a horizontal row across the front face of the belt and in slight forward spaced relationship thereto. It will also be noted that the arm 36 supports the rollers in such a manner that the upper peripheral portions thereof are disposed in a horizontal level approximately mid-way between two shoe plates 24-24.

Work being ground, polished, or otherwise acted upon by the belt 58 is rested upon the rollers and pressed against the abrasive side of the belt. As shown in Fig. 3, work indicated in dotted outline at 60 is supported upon the upper peripheral portions of the rollers and pressed flush against the belt. The work may be supported by the rollers horizontally as indicated in one dotted position, or if desired, it may be tilted so as to be received in the notch 46, as shown in the other dotted position. When the member 60 is tilted into the notch 46, the edges of the work may be beveled to any desired amount limited to the extent of the configuration of the notch. It is to be noted that the work 60 when pressed into engagement with the belt 58 is disposed on a level between the two shoe plates 24-24. Pressure of the work against the belt will cause the belt to shift against the shoes for support and that por-

tion of the belt between the shoes will yield and bow slightly rearwardly. The relative spacing of the shoes with respect to the roller support enables the work to be pressed against the belt with a certain cushioning effect. This is important as it prevents possible breakage of the work in engagement with the belt 58, a highly important feature in the grinding of edges of frangible material such as sheet glass.

Preferably, the shoes 24-24 and their respective linings 26 are slightly spaced from the rear spaces of the belt 58 when the work 60 is not pressed against the belt to prevent undue lining wear. The upper and lower margins of the shoe plates and the linings are turned rearwardly as at 30 to prevent the belt from striking any sharp edges of the linings or the shoes when the work is pressed against the belt. It is understood that during the grinding operation the flexibility of the belt will cause the belt to be backed up or supported by the linings 26, but when the work is removed from engagement with the belt, the latter assumes its normal vertical position spaced from the linings.

The rivets 28 are preferably copper so as to prevent damage to the belt in the event the linings 26 become worn, and the rollers 40 are preferably rubber so as to prevent breakage of fragile material such as glass when they are being ground or polished by the belt 58.

Figs. 5 to 7 illustrate a modification of the invention embodying in general the features of the first disclosure but designed for economical manufacture and use. The device of Figs. 5 to 7 is supported upon a fixed part of a grinding machine frame such as the tubular member 62 similar to the member 10 previously described. Slidably received over one end of the tubular member 62 is a sleeve or collar 64. The collar is joined integrally at its outer end to a bracket plate 66 shaped in the form of a Y and having two divergently extending legs 68-68. The collar 64 and the plate 66 including the legs 68-68 correspond respectively to the collar 12, plate 18, and legs 16-16 previously described. The collar is removably held on the tubular member 62 by means of a set screw 70.

In mounted relationship to the vertical traveling grinding or abrasive belt, indicated in dotted lines at 72 in Fig. 7, the two legs 68-68 are disposed in vertical spaced relation to one another and adjacent to one edge of the back face of the grinding belt. Each leg 68 carries a horizontally extending cylindrically shaped member or rod 74. The rods 74-74 extend horizontally in vertically spaced parallel relationship to one another and transversely to the direction of travel of the belt. The rods 74-74 are adapted to engage the rear face of the grinding belt 72 and function in a similar manner as the shoe plates 24-24 previously described to stabilize the belt as the work is pressed thereagainst. As shown particularly in Fig. 6, each rod 74 is secured to its respective leg 68 by means of a screw member 76 which when tightly threaded rigidly secures the rod to the leg. However, at periodical intervals, the screws 76 may be loosened to permit the rods 74 to be adjusted angularly about their respective axes to bring new peripheral portions thereof into engagement with the grinding belt.

Secured to the bottom leg 68 of the plate 66 is a supporting member or arm 78 which is generally similar to the arm 36 previously described. The arm is bent intermediate its ends to form an L-shaped configuration so as to dispose a forward

portion 80 thereof horizontally across the grinding belt 12 and in slight forward spaced relationship thereto. The forward portion 80 of the bracket is provided with a plurality of laterally extending pins 82 which project forwardly from the device in spaced parallel relationship and in a horizontal row. Each pin 82 carries a correspondingly shaped roller 84 which is preferably formed of deformable or resilient material such as rubber. The rollers 84 and the pins 82 correspond respectively to the rollers 40 and the pins 38 of the previously described embodiment of the invention. The rollers are retained on the respective pins by means of cotter pins 86.

The roller supporting arm 78 including its forward portion 80 is detachably mounted on the bracket plate 60 in a manner similar to that previously described. The rearwardly extending part of the arm is provided with slots which open opposite to one another through the upper and lower edges thereof. The supporting bracket plate 60 is provided with two projecting headed elements 88 and 90 which are slidably received in the slots in the manner previously described in connection with the elements 52 and 54. The headed elements 88 and 90 are offset vertically and horizontally to one another so that when the arm is supported thereby it is rigidly held in place against downward movement. However, the arm may be swung upwardly and quickly freed from the elements for quick detachment therefrom.

The work to be ground, polished, or otherwise acted upon by the belt is supported on the rollers 84 in the manner previously described. So supported, the work is brought into engagement with that portion of the belt traveling between the two rods 14-74. When the work is pressed against the belt 12, the latter is flexed rearwardly into engagement with the rods and stabilized thereby. By virtue of the cylindrical formation, the rods present a relatively small surface area for contact with the belt. This arrangement reduces the wear on the belt. The rods are preferably formed of metal and case-hardened to improve their wearing characteristics, but as wear occurs, the rods may be individually turned on their respective axes by loosening the screws 76 to present new surface areas for contact with the belt.

Figs. 8 and 9 illustrate a modification of the invention wherein the work is supported upon an endless band carried by rotating members generally similar to the rollers 40 and 84 previously described. Referring to Figs. 8 and 9, an arm section corresponding to the roller supporting part 80 previously described is indicated at 92. Carried by the arm section 92 are a plurality of rollers in the form of sheave wheels 94 which may be formed of metal or any suitable rigid material other than rubber, since they are not brought into direct contact with the work. Looped around the rollers is an endless guiding member or band 96 which is formed of yieldable or deformable material such as rubber. To ensure securing of the band 96 to the rollers 94, the latter may be provided with peripheral grooves 98 as shown in Fig. 9 for receiving an internal ribbed portion 100 of the band.

In all three embodiments of the invention, the work supporting means, whether the rollers 40 or 84, or the endless band 96, enables the work to be shifted to and fro across the abrasive face of the grinding belt. This is particularly desirable for grinding the edges of glass sheets and the like and enables the workman to hold a glass sheet either horizontally or at the desired angle, pressing the

same against the grinding belt and simultaneously moving the sheet back and forth across the abrasive face of the belt. The disposition of the belt stabilizing elements, either the shoe plates 24-24 or the cylindrical bars 14-74, on opposite sides of the work engaging area of the belt, enables this portion of the belt to yield slightly and cushion the pressure of the work against the belt.

What I claim is:

1. A device for use on a grinding or polishing machine having a substantially vertically traveling grinding belt comprising, in combination, a U-shaped frame member having the legs thereof arranged in vertically spaced apart relation, flat faced shoes carried on the outer extremities of the legs of said frame member and adapted to slidably engage two vertically spaced apart areas of one side of the vertically traveling grinding belt, a second U-shaped frame member having the legs thereof arranged in horizontally spaced apart relation, means connecting one of the legs of the second frame member to an intermediate portion of the first frame member and disposing the other leg thereof between and in offset parallel relation to the plane of the shoes and on the opposite side of the grinding belt from said shoes, and a row of resiliently faced rollers mounted on said last mentioned leg rotatable about horizontal axes extending perpendicular to the plane of the grinding belt and forming a rest upon which work to be ground by the belt is sidewise movably supported.
2. An attachment for grinding machines having a traveling abrasive belt comprising, in combination, a frame, means carried on the frame for contacting one side of the traveling belt, a plurality of similarly shaped rollers, means mounting the rollers in a row on the frame for rotation about parallel axes and disposing the row of rollers on the side of the belt opposite to said belt contacting means, and a flexible endless band passing around said rollers and forming a rest upon which work may be sidewise movably supported while pressed into engagement with the adjacent side of the traveling belt.
3. In a device for grinding and polishing the edges of glass and similar sheet-like articles and including a substantially vertically movable abrasive endless belt, a supporting bar extending horizontally across one side of the belt and in spaced relation thereto, a collar slidably and adjustably received on said bar, a substantially U-shaped support secured to the collar and arranged so that the two legs of its U-shaped formation are disposed in vertically spaced apart relationship and project from the collar toward the belt, belt engaging members attached to the outer extremities of said legs for engaging longitudinally separated areas of said side of the belt, an arm connected to said U-shaped support and having a part extending substantially horizontally across the side of the belt opposite to said bar and on a level between said belt engaging members, and a horizontal row of similarly formed rollers carried by said part of the arm and being independently journaled thereon about parallel axes extending perpendicular to the plane of the belt, said rollers cooperating together to form a rest upon which a sheet of glass may be supported for edge engagement with the abrasive belt and for movement of the glass sheet transversely to the longitudinal dimension of the belt while so engaged therewith.
4. In a device for grinding and polishing the edges of sheets of glass and the like including a substantially vertically traveling abrasive belt, a

horizontally extending supporting bar positioned in parallel spaced apart relationship to the rear side of the belt, a collar adjustably slidably fitting said bar, means for releasably holding said collar on said bar in adjusted position, a pair of legs secured to the collar and extending toward said belt in vertically spaced apart relation, a belt engaging member carried on the outer extremity of each of said legs for engaging vertically separated areas of said side of the traveling belt, a right angularly formed arm, means for releasably connecting one end portion of said arm to the lower leg of said pair of legs and such that the other end portion of the arm extends transversely across the front side of the belt on a level between the two belt engaging members, a plurality of similarly shaped rollers each having the peripheral portion thereof formed of resilient material, a journal mounting for each of said rollers for providing independent rotation thereof, means securing said journal mountings to the end portion of the arm extending across the front side of the belt and disposing the rollers in a horizontal row with their axes extending parallel to one another and substantially perpendicular to the plane of the traveling belt, the upper peripheral portions of said rollers being arranged to project above the end portion of the arm upon which they are mounted and cooperating together to form a rest upon which a sheet of glass and the like may be supported for edge engagement with the abrasive belt and for movement transversely to the longitudinal dimension of the belt while so engaged therewith.

5. In a device for grinding and polishing the edges of sheets of glass and similar sheet-like articles and including a substantially vertically movable abrasive belt having a front side and a rear side, a supporting frame mounted on the device opposite to the rear side of the belt and including a pair of legs extending toward the rear side of the belt in vertically spaced apart relation to one another, belt engaging members carried on the outer extremities of each of said legs for engaging vertically separated areas of said side of the belt, a right angularly formed arm, means for releasably connecting one end section of said arm to said supporting frame and such that the other end section of the arm extends transversely across the front side of the belt and on a level between the two belt engaging members, a plurality of similarly shaped rollers, a journal mounting for each of said rollers for providing independent rotation thereof, means securing said journal mountings to the end section of the arm extending across the front side of the belt and disposing the rollers in a horizontal row with their axes extending parallel to one another and substantially perpendicular to the plane of the abrasive belt, said rollers cooperating together to form a rest upon which a sheet of glass may be supported for edge engagement with the front side of the belt and for movement of the glass sheet transversely to the longitudinal dimension of the belt while so engaged therewith.

6. A device for grinding and polishing the edges of sheets of glass and similar sheet-like articles and including a substantially vertically movable abrasive belt having a front side and a rear side, a supporting frame mounted on the device opposite to the rear side of the belt and including a pair of legs extending toward the rear side of the belt in vertically spaced apart relation to one another, belt engaging members carried on the outer extremities of said legs for engaging verti-

cally separated areas of the rear side of the belt, a right angularly formed arm, means for releasably connecting one end section of said arm to said supporting frame and such that the other end section of the arm extends transversely across the front side of the belt and on a level between the two belt engaging members, a plurality of similarly shaped rollers, a journal mounting for each of said rollers for providing independent rotation thereof, means securing said journal mountings to the end section of the arm extending across the front side of the belt and disposing the rollers in a horizontal row with their axes extending parallel to one another and substantially perpendicular to the plane of the abrasive belt, and a flexible endless band passing around said rollers and forming a rest upon which a sheet of glass may be supported for edge engagement with the front side of the abrasive belt and providing sidewise movement of the glass sheet transversely to the longitudinal dimension of the belt while so engaged therewith.

7. In a device for grinding and polishing the edges of sheets of glass and the like and including a substantially vertically traveling abrasive belt, an arm, a plurality of similarly shaped rollers each having the peripheral portion thereof composed of resilient material, a journal mounting for each of said rollers, means securing said journal mountings to the arm and disposing the rollers in a row thereon with their respective axes extending parallel to one another, said journal mountings further disposing the rollers so that peripheral portions thereof project equal distances beyond one edge of the arm, and means carried by the arm and attaching the same to a supporting part of the device so that the rollers are disposed in a horizontal row extending transversely across one side of the abrasive belt and with the projecting peripheral portions of the rollers disposed above the arm, said rollers cooperating together to form a cushioned rest upon which a sheet of glass and the like may be supported for edging engagement with the belt and for movement transversely to the longitudinal dimension of the belt while so engaged therewith.

8. In a device for grinding and polishing the edges of sheets of glass and the like and including a substantially vertically traveling abrasive belt having a front side and a rear side, a supporting frame mounted on the device opposite to the rear side of the belt and including a pair of legs extending toward the rear side of the belt in vertically spaced apart relationship to one another, a cylindrically shaped belt engaging member of wear-resistant metallic material carried on the outer extremity of each of said legs and arranged with their axes extending horizontally and parallel to the plane of the belt in order to bring cylindrical surface portions of the members into engagement with vertically separated areas of the rear side of the belt, a right angularly formed arm, means connecting one end section of the arm to said supporting frame and such that the other end section of the arm extends transversely across the front side of the belt on a level between the respective axes of the cylindrical members, a plurality of similarly formed rollers carried by the end section of the arm extending across the front side of the belt and arranged in a horizontal row with their respective axes extending parallel to one another and substantially perpendicular to the plane of the abrasive belt, said rollers cooperating together to form a rest upon which a sheet of glass may be sidewise movably supported

while pressed into engagement with the front side of the abrasive belt, and means providing rotational adjustment of each of said cylindrically shaped members about their respective axes to bring different surface portions thereof into engagement with the rear side of the belt.
